UNITED STATES PATENT OFFICE

2,501,071

ISOMERIZATION OF HYDROCARBONS

Julian M. Mavity, Chicago, Ill., assignor to Universal Oil Products Company, Chicago, Ill., a corporation of Delaware

Application January 16, 1942, Serial No. 426,962

3 Claims. (Cl. 260—683.5)

1

The present invention relates to an improved process for the conversion of hydrocarbons of a saturated character. More particularly, it is concerned with the production of branched chain paraffin hydrocarbons of the same or lower molecular weight from paraffin containing hydrocarbon oils, such as, for example, distillate fractions of petroleum.

More specifically, it is concerned with improvements in processes wherein isomerization of paraffin and naphthene hydrocarbons is effected by contact with metal halide catalysts of the Friedel-Crafts type, and particularly aluminum chloride. This may be accompanied by the formation of branched chain paraffin hydrocarbons containing a fewer number of carbon atoms than the paraffins from which they are formed, such as isobutane, isopentane, isohexanes, etc.

The isomerization of saturated hydrocarbons is becoming increasingly important commercially at the present time due to the fact that hydrocarbons of branched chain structure in the case of paraffin hydrocarbons are generally more reactive than their normal straight chain counterparts. For example, normal butane which is produced in considerable quantities in the production and primary distillation of crude petroleum is apparently not capable of being alkylated by olefinic hydrocarbons in the presence of catalysts, while isobutane can be alkylated with olefins in the presence of a number of different types of catalysts such as metal halides, sulphuric acid, hydrofluoric acid, phosphoric acid and others. By the alkylation of isobutane with butenes, for example, octenes are produced which are readily hydrogenated to isomeric octanes having high antiknock blending values in motor and aviation fuels. In the case of normally liquid paraffin hydrocarbons or mixtures containing such hydrocarbons in admixture with varying amounts of naphthenes such as straight run gasoline fractions, isomerization produces compounds or hydrocarbon mixtures of improved antiknock rating with minimum losses when conditions of operation are properly regulated. The present improved process is applicable to the efficient isomerization of normal butane, of normally liquid hydrocarbons or mixtures thereof either paraffinic or naphthenic or to the treatment of essentially saturated gasoline fractions to improve their antiknock value. The process is applicable to the conversion of a hydrocarbon mixture of a saturated character containing paraffins. This conversion will involve, broadly speaking, the production of branched chain par-

2

affins of the same or lower molecular weight from paraffin-containing oils in, for example, the cracking of distillate fractions of petroleum such as naphtha fractions to produce low-boiling paraffins such as isobutane, isopentane, isohexanes, etc., or in the isomerization of normal or mildly branched chain paraffins to more highly branched chain paraffins of the same number of carbon atoms. The process may be operated in such a manner that both types of reactions occur simultaneously.

In one specific embodiment the present invention comprises subjecting a prepared mixture of a saturated hydrocarbon, a hydrogen halide and hydrogen to contact with aluminum chloride hydrocarbon complexes in a primary stage, further contacting the hydrocarbon products from the primary stage with granular aluminum chloride in a secondary stage while separating hydrocarbon-aluminum chloride complexes, returning said complexes to the primary treating stage, fractionating hydrocarbon products from the secondary stage to separate hydrogen and hydrogen halide which are recycled to the primary stage, and products comprising branched chain paraffins which are recovered as the product of the process, a fraction amenable to further isomerizing treatment which is recycled to the primary stage and heavier hydrocarbon-aluminum chloride complexes which are withdrawn from the process.

The features of the present improved process will be described in more detail in connection with the attached drawing which shows diagrammatically by the use of interconnected units in general side elevation an arrangement of equipment in which the process may be conducted. The drawing is not restricted to any absolute or relative scale and the invention is not limited to the exact description given in connection therewith.

Referring to the drawing, a hydrocarbon charge is admitted to the plant by way of line 1 containing valve 2 to a charging pump 3 which discharges through line 4 containing valve 5 into a heating element 6 disposed to receive heat from a furnace 7. In the preferred operation of the process regulated amounts of hydrogen halide such as hydrogen chloride are introduced to line 8 containing valve 9 to pump or compressor 10 which discharges through line 11 containing valve 12 into line 4, and hydrogen is also preferably introduced by way of line 13 containing valve 14 to a compressor 15 which discharges through line 16 containing valve 17.

and also into line 4, so that a mixture of a hydrocarbon charge, hydrogen halide and hydrogen enters heating element 6.

During passage through heating element 6 the entering mixture is heated to some temperature which is generally within the range of 50 to 125° C., although depending upon the hydrocarbon charge and the degree of isomerization or other conversion ultimately desired temperatures from 10 to 200° C. may be employed. Obviously, when subatmospheric temperatures are used heater 6 may be by-passed or function as a cooler, although means for effecting the by-passing of the element 6 or utilizing the furnace set-up as a cooler are not indicated in the drawing. The process is not limited in respect to the pressures which may be employed except as they may influence the course of the desired reactions in connection with the temperature selected and other factors, and it is within the scope of the present invention to employ pressures as high as 2000 pounds per square inch, although as a rule pressures of from about 100 to about 1000 pounds per square inch are preferred. A hydrogen halide such as hydrogen chloride is generally used in amounts of at least 0.01 mole per mole of hydrocarbon. Hydrogen may or may not be employed depending upon the tendency of the hydrocarbons to undergo undesirable decomposition reactions other than isomerization, and in general, it is seldom necessary to employ more than 3 moles of hydrogen per mole of hydrocarbon undergoing treatment. The conditions utilized in the primary treating stage wherein a hydrocarbon charge is contacted with the hydrocarbon-metal halide complexes formed in the second stage will vary considerably depending upon the exact composition and history of the complex.

The heated materials from element 6 pass through line 18 containing valve 19 to enter the bottom of a primary reactor 20 which preferably has a section 21 filled with granular and relatively inert packing material which functions to distribute the down-flowing streams of liquid hydrocarbon-metal halide complex introduced from line 40 and arising at a point and in a manner to be later described. Reactor 20 is provided with an upper manhead 22 for the introduction of filling material and a lower manhead 23 for its convenient removal if necessary. This reactor is also furnished with a lower draw line 24 containing valve 25 which permits the rejection of the hydrocarbon-metal halide complex after its use in the primary stage since there is generally no benefit in reusing this material.

It has been determined and constitutes a feature of the present invention that hydrocarbon-aluminum chloride complexes formed when saturated hydrocarbons are contacted with granular aluminum chloride catalysts, still have isomerizing potency. These complexes are apparently formed by the union of unsaturated radicals with the aluminum chloride catalyst, the unsaturated components having been formed by incidental and usually minor decomposition reactions. Use is therefore made of these complexes for a preliminary treatment of hydrocarbons to be isomerized and this preliminary treatment produces several benefits under which may be mentioned the utilization of the partly spent primary metal halide catalysts, the preliminary purification of hydrocarbon charges which may at times contain incidental constituents comprising olefins, aromatics and compounds containing oxygen or sulfur and a partial isomerization of the hydro-

carbon charge, this isomerization being substantially completed in the second stage wherein it is contacted with a fresh metal halide catalyst. The products from primary reactor 20 pass through line 26 containing valve 27 and into a secondary reactor containing a bed of granular aluminum chloride.

For insuring continuous operations secondary reactors are utilized in multiple arrangement and 10 may be connected so as to be used in parallel, series of parallel-series connection. Thus, line 28 leads to line 29 containing valve 29 leading to reactor 30, and also to line 44 containing valve 45 leading to a similar reactor 46. Each of the 15 reactors is similarly equipped with lines so that the materials from the primary stage may enter the bottom of the reactor below a fixed bed of granular catalyst, the lower layer hydrocarbon-aluminum chloride complex may be withdrawn, 20 and the reaction products may be withdrawn from the top and passed to subsequent fractionation. Thus, secondary reactor 30 contains a bed of granular catalyst 31 while reactor 46 contains an analogous bed of granular material 47. Reactor 30 has a manhead 32 for the admission 25 of granular aluminum chloride which corresponds to manhead 48 on reactor 46, and a lower manhead 33 for the removal of contaminated material, which corresponds to manhead 49 on reactor 46. Reactor 30 has a lower draw line 33' containing valve 34 through which the said lower layer material may be released, and a branch line 35 containing valve 36 leading to line 37 from 30 which point the lower layer material may be sent back to the primary treating stage. Reactor 46 has similar draw line 50 containing valve 51 for the rejection of lower layer material and a branch line 52 containing valve 53 and leading to line 37. The lower layer complex withdrawn from 35 either secondary stage reactor, as representing any multiple arrangement, passes through line 37 containing valve 38 to a pump 39 which discharges through line 40 containing valve 41 and into the top of reactor 20 above the filling material as already indicated.

For permitting series operation in which primarily treated materials are passed first, through the metal halide bed in reactor 30 and then through a corresponding bed in reactor 46, the 40 upper exit line 56 containing valve 57 has a branch line 58 containing valve 43 and leading to line 44, so that with valve 45 closed the reactants enter the bottom of reactor 46 below the bed of catalyst. Similarly, upper series line 58 45 containing valve 59 has a branch line 56 containing valve 55 which leads to line 28 so that with valve 29 closed the effluent materials from reactor 46 may pass through reactor 30.

During passage of the partially isomerized 50 charge from the primary treating stage through the granular metal halide catalyst in the second stage, isomerization is substantially completed and in the course of the reaction the so-called "lower layer" is formed consisting of hydrocarbon-metal halide complexes. As these are formed they fall downwardly countercurrent to the ascending reactants so that there is a continuous consumption of metal halide. As the depth of the catalyst bed decreases, more may be added 55 by intermittently cutting the reactors out of the circuit and introducing more catalyst through the upper manheads, the stream of reactants passing through other parallel reactors so that the continuity of operation is not interrupted.

55 After the second stage isomerizing treatment,

the products from the reactors are passed to fractionation, through line 56 containing valve 57, if reactor 30 is at the end of the second stage of treatment or from line 58 containing valve 59 if reactor 46 is last in order. The exit lines from the secondary stage all enter a header 60 containing valve 61 which leads to a fractionator 62 as indicated in the drawing, although this fractionator merely diagrammatically represents a fractionating zone in which may be included any number of suitably designed and interconnected fractionators for effecting efficient separation of materials to be recovered, recycled and rejected from the process. As indicated in the drawing, light gases including hydrogen chloride and hydrogen are taken off through line 63 containing valve 64 and leading to recycle pump 65 which discharges through line 66 containing valve 67 and back to process inlet line 4. The isomer fraction such as isobutane in case normal butane is treated, may be withdrawn at a next lower level through line 68 containing valve 69 passed through condenser 70 and thence through line 71 containing valve 72 to a final receiving drum 73 provided with a conventional gas release line 74 containing valve 75 and a liquid draw line 76 for isomer product provided with valve 77. Fractions amenable to further isomerization treatment are withdrawn at the next lower level through line 78 containing valve 79 to recycling pump 80 which discharges through line 81 containing valve 82 back to process inlet line 4. In isomerization of normal butane the material recycled at this point is the unconverted charge. Higher boiling fractions produced incidentally to the main isomerization reactions and of a character not adapted to further isomerization without undue losses and contamination of the catalyst may be withdrawn through line 83 containing valve 84.

The foregoing description utilizes in general the procedure which characterizes the present process although other modifications than those described may be added which facilitate operations without essentially altering the process. For example, a means may be provided for operating the primary reactor 20 at different temperature and pressure conditions than secondary reactors 30 and 46 either by the introduction of heating and cooling devices along the line of flow of the reactants or the recycled materials by the introduction of additional pressuring pumps. Similarly, means may be provided for maintaining substantially constant temperature conditions throughout the reactors such as submerged pipe coils which convey heating or cooling fluids. The relative amounts of hydrogen and hydrogen halide in relation to hydrocarbon charge may also be varied as a means for controlling the nature of the reactions.

The present process is most completely adapted to the utilization of granular and substantially anhydrous aluminum chloride in secondary reactors and the utilization of hydrogen chloride as the hydrogen halide for promoting the isomerization reactions in contact with the aluminum chloride. Obviously, when hydrocarbon charging stocks of diverse character are treated it will be necessary to determine by trial the best con-

ditions of operation. In the case of gasoline fractions which are to be isomerized for the improvement of their antiknock value, conditions will generally have to be controlled within narrow limits to obtain best results.

The following example of operation of the process is given for illustrative purposes but not with the intent of correspondingly limiting the proper scope of the present invention.

10 The hydrocarbon treated was a commercial hexane fraction having an octane number of 58.5 by the motor method which was mixed with 0.12 mole of hydrogen chloride and 0.11 mole of hydrogen per mole of hexane and passed through a treating plant similar to the one described in connection with the drawing, at a temperature of 100° C. under a pressure of 500 lbs., per square inch at a liquid charging rate equivalent to 0.25 volume of liquid fraction per hour per volume of secondary reaction space, that is the space occupied by granular aluminum chloride.

15 Operations were continued over a period of approximately 200 hours during which time there was an average yield of 95% of 80 octane number product.

20 I claim as my invention:

1. A process which comprises contacting relatively low-boiling hydrocarbon material with a bed of solid anhydrous sludge-forming metal halide catalyst of the Friedel-Crafts type under hydrocarbon conversion conditions, withdrawing from said bed an active metal halide sludge produced therein concomitantly with said conversion, and contacting hydrocarbons from said contacting step with said sludge under conversion conditions to continue said conversion through utilization of catalytic activity of said sludge.

25 2. The process of claim 1 in which said metal halide is aluminum chloride.

3. The process of claim 1 in which said hydrocarbon conversion is an isomerization reaction.
